2,123,503

METHOD OF REFINING BLENDED LUBRICATION OILS

Eddie M. Dons and Dwight B. Mapes, Tulsa, Okla., assignors to Mid-Continent Petroleum Company, Tulsa, Okla., a corporation of Delaware

Application July 10, 1936, Serial No. 89,921

5 Claims. (Cl. 196—40)

This invention relates to methods of blending mineral oils. Prior to this invention, in the manufacture of blended lubricating oils, heavy residuum stocks have been mixed with overhead distillates and the resultant blend is then treated with sulfuric acid. This old practice of simultaneously treating constituents of the blends is ordinarily followed in treating distillates blended with reduced crude petroleum containing a substantial percentage of asphaltic material. Our study of this old practice has shown that the asphaltic material in the crude residuum consumes a very large percentage of the acid, which considerably reduces the efficiency of the acid in treating other constituents of the blend.

An object of the present invention is to so treat the constituents of blended oils that the acid will very effectively perform its functions in treating the different kinds of materials. Briefly stated, instead of beginning with the step of treating the blended materials, we begin by selecting the fraction that is most difficult to treat, for example, an asphalt-containing residuum, and subject it to the action of sulfuric acid. After removing the acid sludge, the treated oil is blended with the distillate stock, and the resultant blend of treated and untreated oil is then treated with additional acid.

In a specific example, hereafter set forth, we will show how the new method (compared with the above-mentioned old practice) may be employed to reduce the quantity of acid, as well as the temperature of the acid treatment, and at the same time obtain improved results.

With the foregoing and other objects in view, the invention comprises the novel method hereinafter more specifically described and shown in the accompanying drawing, which illustrates one form of the invention. However, it is to be understood that the invention comprehends changes, variations and modifications within the scope of the claims hereunto appended.

The drawing is a diagrammatical view of a system embodying the features of this invention.

As an illustration of the different kinds of oils to be blended, we have shown a tank 1 for residuum, which may be reduced crude petroleum containing a substantial percentage of asphaltic material, and a tank 2 for an overhead distillate stock to be blended with the residuum. A desirable lubricating oil can be produced by blending materials of this kind.

3 designates a supply of sulfuric acid, and 4 is a chamber wherein the residuum from tank 1 is treated with the acid. In the preferred form of

the invention, the stock to be treated is mixed with a diluent or solvent from a supply tank 5. This diluent is preferably a normally liquid hydrocarbon of the paraffin series, or cyclo-paraffin series, substantially free from constituents that react with sulfuric acid. It may be selected from pentane, hexane, heptane, or other members of either of said series. Mixtures of such hydrocarbons having about 3 to 8 carbon atoms may be employed as a solvent or diluent.

If desired, a normally gaseous hydrocarbon diluent, such as propane, butane, etc., may be employed, but in this event, the system should be designed to operate under a pressure high enough to retain the diluent in a liquid condition.

The residuum tank 1 is provided with a discharge pipe 6 connected to a pipe 7 which leads to the acid treater 4, a mixer 8 being located in the pipe line 7. The diluent tank 5 is provided with a discharge pipe 9 leading to the pipe 7. The acid receptacle 3 is connected to the pipe 7 by means of a pipe 10.

The residuum and diluent are united in the pipe 7 which receives acid from the pipe 10, and after passing through the mixer 8, these materials enter the chamber 4, where the acid sludge settles to the bottom, and is withdrawn through a discharge pipe 11.

The acid-treated solution, discharged from the top of the chamber 4, flows through pipe 12 to a pipe 13 leading to a mixer 14 which discharges through a pipe 15 to a chamber 16.

The acid receptacle 3 is provided with a discharge pipe 17 connected to the pipe 13. The distillate tank 2 discharges through a pipe 18 leading to the pipe 12.

It will now be understood that the treated solution passing from the pipe 12 is mixed with distillate from tank 2, and acid from the receptacle 3, and that the resultant mixture is discharged into the chamber 16. The acid sludge is discharged through a pipe 19 at the bottom of the chamber 16, while the diluted blend of residuum and distillate is discharged from the top, through a pipe 20. This blend of lubricating oil stocks may be further refined by contacting with clay which serves as a neutralizing and decolorizing agent.

As a specific illustration of one form of the invention, we will refer to the manufacture of a blended lubricating oil wherein 40 per cent of the blend was a reduced crude petroleum from the Mid-Continent field, having a Saybolt universal viscosity of 122 at 210° F., and containing a substantial proportion of asphalt and other impuri-

ties to be removed by the acid. The other constituent, amounting to 60 per cent of the blend, was an overhead distillate from a similar crude oil.

5. The reduced crude, or residuum, diluted with 2½ parts of pentane to one part of the residuum, was treated with about 14 pounds of 98 per cent sulfuric acid per barrel of the residuum. The temperature of this acid treatment was 80° F. to 85° F.

10. The resultant acid-treated solution was mixed with the distillate to form a blend, which was then treated with ten pounds of 98 per cent sulfuric acid per barrel of oil in the blend. The 15 acid-treated blend diluted with pentane, which may be regarded as the material discharged through the pipe 20, was then contacted with clay at a temperature of 375° F., thereby subjecting the blend to a neutralizing and decolorizing 20 operation, and at the same time distilling the pentane, which is condensed and recovered. In using three fourths of a pound of clay per gallon of the blended oil, the product had a 2½ Tag. Rob. color.

25. An ordinary commercial practice in treating the above mentioned oil stocks consists in treating the entire blend of residuum and distillate at a temperature of 120° F. to 130° F., using thirty-eight pounds of 98% sulfuric acid per barrel of the blend, and thereafter contacting the acid-treated blend with 1¼ pounds of clay per gallon of the blend, to obtain a Tag. Rob. color of 2 to 2.5.

30. In the specific example of the new method we obtained a better color (2½ instead of 2 to 2.5), using less acid (a total of about 15.6 pounds per barrel of the blend instead of 38 pounds), while treating at 80° F. to 90° F., instead of 120° F. to 130° F., and in the contacting operation we used 35 three-fourths of a pound of clay per gallon of blend, instead of 1¼ pounds. We thus obtained a substantial improvement at each stage of the operation, and it will, of course, be understood that corresponding results can be obtained in 40 treating various other kinds of blends, especially combinations of residuums and distillates to produce blended lubricating oils.

45. We claim:

1. In the art of refining blended lubricating oils, the steps which comprise treating a viscous petroleum residuum with sulfuric acid, thereafter adding a less viscous lubricating oil distillate to the treated viscous oil, and treating the 5 combined constituents of resultant blend with additional sulfuric acid.

2. In the art of refining blended lubricating oils, the steps which comprise treating a viscous petroleum residuum stock with sulfuric acid, removing the resultant sludge, adding a less viscous lubricating oil distillate to the treated viscous residuum, treating the combined oils with sulfuric acid, and separating acid sludge from the treated blend of residuum and distillate.

15. 3. In the art of refining blended lubricating oils, the steps which comprise diluting a petroleum residuum with a normally liquid hydrocarbon diluent selected from the paraffin series and cyclo-paraffin series, treating the diluted 20 residuum with sulfuric acid, mixing the treated solution with a lubricating oil distillate, treating the diluted oils with sulfuric acid, and removing the diluent from the treated blend of residuum and distillate.

25. 4. In the art of refining blended lubricating oils, the steps which comprise diluting a viscous petroleum residuum with a liquid hydrocarbon diluent selected from the paraffin series and cyclo-paraffin series, said diluent being substantially free of constituents that react with sulfuric acid, treating the diluted residuum with sulfuric acid, mixing the treated solution with a less viscous lubricating oil distillate, treating the resultant diluted oils with sulfuric acid, and thereafter removing the diluent from the treated blend of distillate and residuum.

30. 5. In the art of refining blended lubricating oils, the steps which comprise diluting a viscous petroleum residuum with pentane, treating the 35 diluted residuum with sulfuric acid, mixing the acid-treated solution with a lubricating oil distillate, treating the mixture with sulfuric acid, and removing the pentane from the treated blend of residuum and distillate.

45. EDDIE M. DONS.
DWIGHT B. MAPES.

CERTIFICATE OF CORRECTION.

Patent No. 2,123,503.

July 12, 1938.

EDDIE M. DONS, ET AL.

It is hereby certified that error appears in the above numbered patent requiring correction as follows: In the preamble to the grant, name of assignee, for "MID-CONTINENT PETROLEUM COMPANY" read MID-CONTINENT PETROLEUM CORPORATION; and line 13 of the grant and in the heading to the printed specification, for "Mid-Continent Petroleum Company" read Mid-Continent Petroleum Corporation, as shown by the record of assignments in this office; and that the said Letters Patent should be read with this correction therein that the same may conform to the record of the case in the Patent Office.

Signed and sealed this 4th day of October, A. D. 1938.

Henry Van Arsdale
